UNITED STATES PATENT OFFICE

136,095

DESIGN FOR AN OPHTHALMIC-MOUNTING LENS

Austin B. Chaney, San Francisco, Calif., assignor
to American Optical Company, Southbridge,
Mass., a voluntary association of Massachu-
sets

Application November 24, 1941, Serial No. 104,269

Term of patent 14 years

To all whom it may concern:

Be it known that I, Austin B. Chaney, a citizen of the United States of America, residing at San Francisco, in the county of San Francisco and State of California, have invented a new, original, and ornamental Design for an Ophthalmic-Mounting Lens, of which the following is a specification, reference being made to the accompanying drawing, forming a part thereof.

Fig. 1 is a face view of an ophthalmic-mounting lens showing my new design; and

Fig. 2 is a top plan view thereof.

The essential feature of my design for an ophthalmic-mounting lens resides in the specific configuration thereof as shown.

I claim:

The ornamental design for an ophthalmic-mounting lens, substantially as shown and described.

AUSTIN B. CHANEY.
